UNITED STATES PATENT OFFICE.

JOSIP JURICICH, OF PITTSBURGH, PENNSYLVANIA.

HORSE-CURRYING DEVICE.

1,335,441.

Specification of Letters Patent. Patented Mar. 30, 1920.

Application filed December 21, 1917, Serial No. 208,247. Renewed February 18, 1920. Serial No. 359,541.

To all whom it may concern:

Be it known that I, JOSIP JURICICH, a citizen of Jugo-Slavia, residing at Pittsburgh, in the county of Allegheny and State 5 of Pennsylvania, have invented certain new and useful Improvements in Horse-Currying Devices, of which the following is a specification.

This invention relates to certain new and 10 useful improvements in horse currying devices.

The primary object of the invention is the provision of a device adapted for currying horses, either by manual or motive 15 power, the arrangement being such that the animal is cleaned by brushing and scraping in an expeditious and easy manner.

A further object of the device is to provide a currying device having simultaneously operable combing and brushing means, provision being made for collecting hair and dirt within the device to be readily emptied therefrom when desired.

With these general objects in view and 25 others that will appear as the nature of the invention is better understood, the same consists in the novel construction, combination and arrangement of parts hereinafter more fully described, illustrated in the accompanying drawings, and then claimed.

In the drawings forming a part of this application and in which like designating characters refer to corresponding parts throughout the several views:

35 Figure 1 is a side elevation of the device.

Fig. 2 is a central longitudinal sectional view thereof.

Fig. 3 is a transverse sectional view of the same.

40 Fig. 4 is a top plan view of the device with the upper portion thereof removed and the gear casing shown in section.

Fig. 5 is a perspective view of the conveyer.

45 Figs. 6, 7, 8, and 9 are transverse sectional views of different forms of combs employed.

Fig. 10 shows portions of three rollers employed with the conveyer.

50 Figs. 11 and 12 are perspective views of portions of removable guards employed for the combs of the device.

Figs. 13 and 14 are perspective views of

other forms of guards and scrapers which may be employed, and

Figs. 15 and 16 are perspective views of 55 further modified forms of guards and scrapers.

In the drawings a device is illustrated having an elongated casing 10 of substantially the size of the usual currycomb, the 60 same having an open bottom but provided with a cover 11 hingedly mounted as at 12, a centrally arranged casing 13 being provided upon the cover serving as a handle for grasping the device as well as for a housing 65 for an electric motor 14 when motive power is employed.

A brush 15 is journaled by means of its axle 16 transversely within the casing 10 adjacent one end thereof in a manner to allow the brush to project beneath the lower side edges 17 of the casing while a plurality of the comb devices are arranged with their shafts 18 spaced apart and journaled through the said casing adjacent the brush 75 15, the same employing a plurality of combs 19 secured radially projecting from the shafts 18.

The axle 16 and shafts 18 being arranged in parallelism have their opposite ends projected through the sides of the casing 10 and each provided with a pinion 20 while gears 21 interposed between the adjacently arranged pinions operatively connect all of the pinions together upon each side of the 85 casing 10 whereby the combs and the brush are adapted for simultaneous operation.

When employed without a motor, the housing 13 is readily grasped by the operator and the brush 15 and comb members 90 forcibly brought into engagement with the animal. The motor 14 however, is preferably employed mounted in the housing 13 upon a suitable platform 13' secured to the interior of one side wall of the housing, as 95 best illustrated in Fig. 3 of the drawing. The power shaft 20' for the motor is provided with a gear 21' arranged in constant mesh with a pinion 22 carried by a driven shaft 23 journaled transversely through the 100 casing 10 and having pinions 24 upon its opposite ends in constant mesh with the central ones of said gears 21. Covers 25 are provided for the gears upon the opposite sides

of the casing 10 while the circuit wires 26 for the motor 14 pass outwardly through the housing 13 through a perforation 27 in the top thereof. It will be readily understood that by turning on the motor 14, the driven shaft 23 operates in revolving the brush and the combs in the same direction and by applying the device to an animal, the hair will be operated upon by said combs 10 and brush.

A curved guard 28 is adjustably mounted within the casing 10 overlying the brush 15 and having a toothed edge 29 adapted to be brought into engagement with the said brush when desired. The said guard is provided with a flange 30 arranged beneath springs 31 mounted upon the adjacent end of the casing 10 permitting the vertical adjustment of the said guard by means of inwardly extending lugs 31.

A similar guard 32 is provided for the brush at the opposite end of the brush 15 being removably suspended within the casing by means of terminal hooks 33. Suitably curved pans 34 and 35 of similar construction are suspended within the casing adjacent the said guards by means of end hooks 36, the guard 32 underlying and being spaced from the adjacent end of the pan 35, which pan underlies and is spaced from the adjacent end of the pan 34 while the brush guard 28 is arranged beneath and spaced from the adjacent end of a comb 18.

In operating the combs and brushes in the direction indicated by the arrow in Fig. 2, the dirt and hair which is separated by the device will be thrown upwardly into the pans 34 and 35 and also upon the guard 32, the end flanges 37 of the pans assisting to retain the particles thereon while the curvature of the guard 32 and the pans assist the particles in the path of movement to their receiving positions upon the end guard 28. Whenever desired the device may be tilted with the brush 15 downward, thereby moving all of the particles from the pans 34 and 35 into the space above the guard 28. The slide door 38 is provided in the cover 11 of the casing 10 overlying the guard 28 for allowing the removal of all particles from the casing 10 by opening the said door. In this manner, the combings are prevented from accumulating within the device and the same is readily maintained in a cleanly condition while the device is readily operable. It will be noted that the guards 28 and 32 as well as the pans 34 and 35 may be readily removed when the cover 11 is opened.

A conveyer brush 39 in the form of a belt or apron is arranged within the casing 10 upon transversely journaled shafts 40 at a point above the guards 34 and 35 and beneath the motor 14. Three of these shafts 65 are shown arranged in the same plane and

parallel with the aforementioned shaft 23, it being understood that the shaft 23 is revolved by the motor in the manner heretofore described.

The shaft 23 is arranged centrally with teeth 41 while the shafts 40 are provided with similar teeth 42, which teeth are adapted to engage within a centrally arranged perforated portion 43 of the conveyer 39 for operatively moving the said conveyer in substantial contact with the guards 34, 35, and 32 in the direction of the receiving guard 28. A suitable scraper or cleaner 43^a is adjustably carried above the conveyer 39 at any convenient point and preferably above the brush 15 for causing any removed particles upon the conveyer to drop back on the guard 28. Guards or cleaners such as 43^b, 43^c, 43^d, 43^e, 43^f, or 43^g as shown respectively in Figs. 11, 12, 13, 14, 15, and 16 may be substituted for the cleaner 43 in the casing 10 if desired. The comb shafts 18^a, 18^b, 18^c, 18^d as shown respectively in Figs. 6, 7, 8, and 9 may be substituted for the combs 18 if found desirable. It will be understood that in operation, the motor 14 being set in motion, the combs 18 and the brush 15 will revolve as heretofore noted while the conveyer 39 will move in the direction as indicated by the arrows in Fig. 2 to sweep the particles forwardly over the guards 34 and 35 as well as the guard 32 and into the guard member 28 whereby the same may be emptied by opening the door 38. A self-cleaning motor driven curry-comb and brush is arranged adapted for quick and thorough work during the operation thereof.

What I claim as new is:—

1. A currying device comprising a casing, a brush journaled adjacent one end of the casing, a plurality of comb members journaled within the casing adjacent the brush, gear connections between the said brush and combs, a housing upon said casing, a motor within the said housing, a driven shaft journaled through the casing operatively geared between the motor and said geared connections, and spaced overlapping receiving pans arranged within the casing overlying said combs with the said shaft positioned therebetween, and an outlet door provided for the casing adjacent the said brush.

2. A device of the class described comprising a casing, a brush transversely journaled adjacent one end of the casing and projecting therebeneath, revolving combs arranged adjacent the brush, a curved receiving pan arranged above the said brush and the adjacent comb, a guard for the brush adjustably mounted upon the adjacent end of the casing having a toothed edge adjacent the brush, and an outlet door carried by the top of the casing above the said guard.

3. A currycomb comprising a casing, a

brush and combs arranged projecting from the lower side thereof, a receiving guard at one end of the casing and a conveyer adapted for movement above the combs and brush 5 toward the said guard.

4. A currycomb comprising a casing, simultaneously operable revolving combs and brush arranged in the lower side thereof, inclined dirt receiving separated guards above 10 the said combs and brush, an adjustable dirt receiving guard arranged at one end of the casing adjacent the brush, and a simultaneously operable brush conveyer in the upper portion of the casing in substantial contact 15 with the said guards adapted for movement toward the said receiving guard.

5. A currycomb comprising a casing, si-

multaneously operable revolving combs and brush arranged in the lower side thereof, inclined dirt receiving separated guards above 20 the said combs and brush, an adjustable dirt receiving guard arranged at one end of the casing adjacent the brush, and a simultaneously operable brush conveyer in the upper portion of the casing in substantial contact 25 with the said guards adapted for movement toward the said receiving guard, an outlet door in the casing above the said receiving guard, a cleaner for said conveyer arranged above the latter and an operating motor for 30 the said conveyer combs and brush.

In testimony whereof I affix my signature.

JOSIP JURICICH.
